UNITED STATES PATENT OFFICE.

KENNETH E. MARSH, OF GROTON, NEW YORK, ASSIGNOR TO CORONA TYPEWRITER COMPANY, INC., OF GROTON, NEW YORK, A CORPORATION OF NEW YORK.

TYPEWRITING MACHINE.

1,424,841.

Specification of Letters Patent. Patented Aug. 8, 1922.

Application filed July 22, 1920. Serial No. 398,109.

To all whom it may concern:

Be it known that I, KENNETH E. MARSH, a citizen of the United States, and resident of Groton, in the county of Tompkins and State of New York, have invented certain new and useful Improvements in Typewriting Machines (Case No. 178), of which the following is a specification.

This invention relates to improvements in typewriting machines, and more particularly to the line-spacing mechanism thereof, and has for one of its objects the provision of simple and efficient mechanism for rotating a platen for line spacing, readily adjustable for single or double spacing, and so constructed as to prevent overthrow or excessive rotation of the platen. Another object of the invention is to provide a line spacing mechanism of simple, light, compact and inexpensive construction especially adapted for use on small portable typewriting machines, such as the well-known Corona folding typewriter, and said mechanism consisting of a minimum number of parts and being constructed substantially entirely of sheet metal. Other objects of the invention will more fully appear from the following description of the invention in detail, with reference to the accompanying drawings.

In the drawings, Fig. 1 is a top plan view showing one end of a platen carriage and platen with the improved line spacing mechanism associated therewith, the parts being shown in normal position when adjusted for double spacing;

Fig. 2 a view similar to Fig. 1 showing the line-space mechanism adjusted for single spacing;

Fig. 3 a front elevation, partly in vertical section, showing the position of the parts at the end of the line-spacing movement of the line-space lever;

Fig. 4 a vertical transverse section on the line IV—IV of Fig. 1;

Fig. 5 a view similar to Fig. 4, the line-space lever being shifted to the position shown in Fig. 3;

Fig. 6 a front elevation, the parts being in the position shown in Fig. 1;

Fig. 7 a section on the line VII—VII of Fig. 6;

Fig. 8 a perspective view of the adjustable stop;

Fig. 9 a perspective view of the supporting bracket; and

Fig. 10 a perspective view of the line-space lever and parts carried thereby.

Referring to the drawings by numerals, 1 designates the bottom plate of a sheet metal carriage having integral end brackets or upstanding portions 2 in which the shaft 3 of platen 4 is journaled adjacent the ends of the platen. The platen carriage, a part of the left-hand end only of which is shown, 65 may, however, be constructed in various ways and be mounted on a bed or other support in any suitable manner to travel endwise for letter spacing. The line-space wheel may be connected to rotate with the 70 platen in any suitable manner. I have shown a well-known form of line-space wheel comprising a ring or annulus 5 having a toothed perimeter and held on the hub 6 of the platen 4 to rotate with the platen. 75 The usual finger wheel 7 is fixed on the end of the platen shaft.

A sheet metal bracket or angle plate 8 is mounted on the platen carriage with the vertical portion thereof abutting against the 80 inner side of the left-hand end bracket 2 of the carriage. The base flange of plate 8 is secured to the base plate 1 of the carriage by screws 9, and the vertical portion of the angle plate is provided with an aperture 10 85 registering with the platen shaft bearing opening in end bracket 2. Aperture 10 is of greater diameter than the platen shaft 3 and the reduced outer end portion 6^a of the platen hub 6 fits in said aperture with the 90 circumferential shoulder formed adjacent the outer end of the hub at the inner end of reduced portion 6^a abutting against the inner face of the angle plate 8.

The vertical portion of angle plate 8 is 95 provided adjacent its upper end with two integral laterally extending parallel arms 11 and 12 terminating intermediate the finger wheel 7 and end bracket 2 and provided with apertures 13 and 14. Arms 11 and 12 are 100 spaced apart from front to rear a distance substantially equal to the diameter of the line-space wheel 5, and are located above and at opposite sides of the platen shaft 3. Aperture 13 is provided with screw threads and a pivot rod 15 supported at one end in aperture 14 is threaded at its other end and screwed in aperture 13.

The line-space lever 16 is formed of sheet metal and provided at its lower end with 110 a forwardly extending horizontal portion 17

bent upwardly at its forward end to provide a short vertical arm 18 parallel with the lever 16. Lever 16 is provided with an integral finger piece 16^a at its upper end, bent 5 at a right angle to the plane of the lever. The horizontal portion 17 is materially shorter than the distance between arms 11 and 12, and lever 16 and arm 18 are provided just above the connecting member 17 10 with apertures 19 for supporting the lever and its connected arm to rock and slide in unison on rod 15.

A curved arm or rigid line-space pawl 20 formed integrally with the line-space lever 15 extends inwardly and downwardly over the upper edges of end bracket 2 and plate 8 to a point overhanging but out of contact with the ratchet wheel 5, and an angular stop lug 21 extends inwardly from the lever 16 below pawl 20, the free end of said lug extending vertically downward below the horizontal plane of the pivotal axis of the lever. The vertical edge of the free end of angular stop lug 21 is adapted to abut against the outer face of the end bracket 2 of the carriage to limit the pivotal movement of the line-space lever toward the left or away from the line-spaced wheel.

A coil spring 22, connected at its upper 30 end with part 17 of the line-space lever at the outer side of rod 15, extends forwardly and downwardly at the rear of the platen shaft 3 and is connected at its lower end with a lug 23 stamped from the end bracket 35 2 of the carriage at a point under the platen shaft. The spring 22 serves to rock lever 16 about shaft 15 until arrested by lug 21, and to simultaneously pull the lever forwardly along said shaft 15. The normal position of the lever longitudinally of shaft 15 is determined by an adjustable stop lever 24 pivotally held by a pivot screw 25 on the upper side of a horizontal arm 26 formed on angle plate 8 forward of the line-space lever 40 16. Stop lever 24 has two straight stop faces or edges 27 and 28 at right angles to each other and different distances from its pivot and adapted to be engaged by the forward side of the line-space lever in different adjusted positions of the stop lever to limit the 45 forward sliding movement thereof under the influence of spring 22, and thus determine the initial or normal position of pawl 20 relatively to the teeth of the ratchet wheel 5 in single and double spacing. The stop edge 27 cooperates with lever 16 when the mechanism is set for single spacing, and stop edge 28 cooperates with lever 16 when the mechanism is set for double spacing. A lug 50 29 stamped down from stop lever 24 is adapted to engage a shoulder 30 on arm 26 to determine the single-space adjustment of the stop lever, and a friction washer 31 interposed between the lever and arm 26 holds 55 the lever in its adjusted position. Both the

stop edges 27 and 28 may overhang the rear edge of arm 26 in single and double-space positions of the lever 24, respectively, but I prefer that stop edge 28 be in the same plane as the rear edge of arm 26 when the stop 70 lever is set for double spacing, so that the line-space lever will abut against arm 26 as well as the stop lever, as shown in Figs. 1, 4 and 7.

As heretofore described, the line-space 75 pawl 20 is normally free of the teeth of the ratchet wheel so that the platen may be rotated in either direction by finger wheel 7. The usual detent roller 32, journalled in a yoke on the free end of a flat spring 33 held to the carriage by a screw 34, is provided for holding the platen against accidental rotation. Overthrow or excessive rotation of the platen when the line-space lever is quickly or violently operated is prevented 80 by an overthrow lock or rigid pawl 35 formed as an integral inwardly and slightly downwardly curved extension of the arm 18.

The pawl 35 is shorter than pawl 20 and passes inwardly and downwardly through an opening 36 in angle plate 8 when the line-space lever is swung toward the right. The end of pawl 35 engages the longer face of one of the teeth of ratchet wheel 5 at a point forward of a vertical plane through the longitudinal axis of the platen to prevent further movement of the ratchet wheel and line-space lever when the line-space lever is rocked toward the right to a predetermined point as shown in Figs. 3 and 5. The final position of the line-space lever and pawls 20 and 35 is always the same, this position being shown in Figs. 3 and 5, and the extent of pivotal movement of the line-space lever is always the same, but the extent of sliding movement of the lever and point of engagement of pawl 20 with the ratchet wheel varies with the adjustment of stop 24 which determines the initial position of the lever longitudinally of the sliding and pivotal support 100 15. 110

What I claim is:

1. In a typewriting machine, the combination of a rotatably supported platen, a ratchet wheel rotatable with said platen, a pivotally and slidably supported line-space lever, a fixed pawl carried by said lever adapted to engage and rotate the ratchet wheel, and an overthrow locking pawl carried by said lever adapted to engage the ratchet after a predetermined movement of the line-space lever.

2. In a typewriting machine, the combination of a rotatably supported platen, a ratchet wheel rotatable with said platen, a line-space lever pivotally supported to rock about an axis parallel with the plane of the ratchet wheel, and a line-space pawl and an overthrow locking pawl spaced apart longitudinally of the pivotal axis of the 125 130

lever and connected to move in unison therewith.

3. In a typewriting machine, the combination of a rotatably supported platen, a 5 ratchet wheel rotatable with the platen, a line-space lever pivotally supported to rock about an axis extending transversely of the platen, and a pair of fixed pawls carried by said lever and spaced apart longitudinally 10 of the pivotal axis thereof adapted to successively engage the ratchet wheel when the lever is rocked in one direction.

4. In a typewriting machine, the combination of a rotatably supported platen, a 15 ratchet wheel rotatable with the platen, a line-space lever, means supporting the lever for pivotal and sidewise movements, a pawl operable by said lever for rotating the ratchet wheel, means for regulating the extent 20 of sidewise movement of the lever at will, and means for always arresting the pivotal movement of the lever in opposite directions around its axis at the same two points.

25 5. In a typewriting machine, the combination of a rotatably supported platen, a ratchet wheel rotatable with the platen, a line-space lever, means supporting the lever for pivotal and sidewise movements, a 30 pawl operable by said lever for rotating the ratchet wheel, two independent arresting devices movable with the lever for arresting the pivotal movement of the lever in different directions at two fixed points, and adjustable means for limiting the extent of 35 the sidewise movement of the lever.

6. In a typewriting machine, the combination of a rotatably supported platen, a ratchet wheel rotatable with the platen, a 40 line-space lever, means supporting the lever for pivotal and sidewise movement, a pawl operable by said lever for rotating the ratchet wheel, and an overthrow pawl operable by the lever adapted to engage the 45 ratchet wheel subsequently to the engagement of the other pawl therewith to limit the pivotal movement of the lever in one direction.

7. In a typewriting machine, the combination of a rotatably supported platen, a 50 ratchet wheel rotatable with the platen, a line-space lever, means supporting the lever for pivotal and sidewise movement, a pawl operable by said lever for rotating the 55 ratchet wheel, an overthrow pawl operable by the lever adapted to engage the ratchet wheel subsequently to the engagement of the other pawl therewith to limit the pivotal movement of the lever in one direction, and 60 adjustable means for limiting the sidewise movement of the lever.

8. In a typewriting machine, the combination of a rotatably supported platen, a ratchet wheel rotatable with the platen, a

line-space lever, means supporting the lever 65 for pivotal and sidewise movement, a pawl operable by said lever for rotating the ratchet wheel, an overthrow pawl operable by the lever adapted to engage the ratchet wheel subsequently to the engagement of 70 the other pawl therewith to limit the pivotal movement of the lever in one direction, adjustable means for limiting the sidewise movement of the lever, a spring for normally swinging and sliding the lever in one direction to carry said pawls away from the ratchet wheel, and means for limiting the pivotal movement of the lever by the spring.

9. In a typewriting machine, the combination of a rotatably supported platen, a 80 ratchet wheel rotatable with the platen, a line-space lever, means supporting the lever for pivotal and sidewise movement, a pawl operable by said lever for rotating the ratchet wheel, an overthrow pawl operable 85 by the lever adapted to engage the ratchet wheel subsequently to the engagement of the other pawl therewith to limit the pivotal movement of the lever in one direction, adjustable means for limiting the sidewise movement of the lever, a spring for normally swinging and sliding the lever in one direction to carry said pawls away from the ratchet wheel, and a stop carried by said lever adapted to engage a relatively fixed 90 abutment to limit the pivotal movement of the lever by said spring.

10. In a typewriting machine, the combination of a platen, a ratchet wheel connected to rotate with the platen, a slidably and 100 pivotally supported line-space lever, a pawl carried by said lever for rotating the ratchet wheel, means for arresting the pivotal movement of the lever at two fixed points, and adjustable means for limiting the sliding 105 movement of the lever.

11. In a typewriting machine, the combination of a platen, a ratchet wheel connected to rotate with the platen, a slidably and pivotally supported line-space lever, a 110 pawl carried by said lever for rotating the ratchet wheel, means for arresting the pivotal movement of the lever at two fixed points, adjustable means for limiting the sliding movement of the lever, and a spring 115 for normally swinging and sliding the lever to one limit of its movement.

12. Line-spacing mechanism comprising a rotatable platen, a ratchet wheel connected to rotate with the platen, a line-space lever 120 mounted adjacent the line-space wheel to swing about and slide longitudinally of an axis extending transversely of the platen and having a uniform pivotal movement at all times, adjustable means for limiting the sliding movement of the lever, a pawl carried by said lever adapted to engage and rotate the ratchet wheel, and spring means for 125

- restoring the lever after a line-spacing movement thereof.
13. In a typewriting machine, the combination of a platen carriage, a rotatable platen mounted on the carriage, a ratchet wheel held to rotate with the platen, a shaft supported on the carriage adjacent the line-space wheel and parallel therewith, a line-space lever pivotally and slidably mounted on said shaft, a pair of fixed pawls carried by the lever spaced apart longitudinally of the shaft and adapted to successively engage the ratchet wheel, a spring connected with the lever and carriage for forcing the lever about and longitudinally of the shaft to carry the pawls away from the ratchet wheel, an abutment on the lever adapted to engage a fixed part on the carriage to limit the pivotal movement of the lever by the spring, and an adjustable stop mounted on the carriage for determining the normal position of the lever lengthwise of the shaft.
14. In a typewriting machine, the combination of a platen carriage, a platen rotatably supported on the carriage, a line-space wheel rotatable with the platen, a line-space lever mounted on the carriage to swing lengthwise of the platen and slide transversely of the platen, a line-space pawl and an overthrow pawl carried by the lever and adapted to engage the ratchet wheel at circumferentially spaced points successively, spring means for restoring the lever after a line-spacing movement thereof, means arresting the pivotal movement of the lever at a fixed point on its return stroke, and adjustable means for determining the normal position of the lever longitudinally of its axis.
15. In a typewriting machine, the combination of a platen carriage, a platen rotatably supported on the carriage, a rod supported on the carriage transversely of the platen, a ratchet wheel rotatable with the platen, a sheet metal line-space lever slidably and pivotally held to said rod and provided with integral line-spacing and overthrow pawls spaced apart longitudinally of the rod and adapted to successively engage the ratchet wheel, and a single spring connected at its ends with said lever and carriage for restoring the lever.
16. In a typewriting machine, the combination of a platen carriage, a platen rotatably supported on the carriage, a rod supported on the carriage transversely of the platen, a ratchet wheel rotatable with the platen, a sheet metal line-space lever slidably and pivotally held to said rod and provided with integral line-spacing and overthrow pawls spaced apart longitudinally of the rod and adapted to successively engage the ratchet wheel, a single spring connected at its ends with said lever and carriage for restoring the lever, and an adjustable stop

mounted on the carriage for determining the initial position of the lever longitudinally of the rod.

17. In a typewriting machine, the combination of a platen carriage, a platen rotatably supported on the carriage, a rod supported on the carriage transversely of the platen, a ratchet wheel rotatable with the platen, a sheet metal line-space lever slidably and pivotally held to said rod and provided with integral line-spacing and overthrow pawls spaced apart longitudinally of the rod and adapted to successively engage the ratchet wheel, a single spring connected at its ends with said lever and carriage for restoring the lever, and an adjustable stop mounted on the carriage for determining the initial position of the lever longitudinally of the rod, said lever having a uniform pivotal movement in all adjusted positions of said stop.

18. In a typewriting machine, the combination of a rotatable platen-feeding element, a device cooperating with said element to rotate the same, means for swinging said device through a fixed arc about an axis extending transversely of the axis of rotation of said element and shifting said device laterally longitudinally of the axis of its swinging movement, and adjustable means for controlling the extent of lateral movement of said device.

19. In a typewriting machine, the combination of a rotatable platen-feeding element, a device cooperating with said element to rotate the same, means for swinging said device through a fixed arc about an axis extending transversely of the axis of rotation of said element and shifting said device laterally longitudinally of the axis of its swinging movement, spring means for normally swinging said device away from said element and shifting the device laterally, and means for varying the extent of the lateral shifting movement of said device by said spring means.

20. In a typewriting machine, the combination of a platen feed wheel, a slidably and pivotally mounted feed pawl, manually operable means for swinging said pawl through a fixed arc about an axis extending transversely of the axis of the feed wheel, spring means for normally swinging said pawl away from the wheel and sliding the same laterally, and adjustable means for arresting the sliding movement of the pawl under the influence of said spring means.

21. In a typewriting machine, the combination of a platen carriage, a platen rotatably mounted on the carriage, a ratchet wheel rotatable with the platen, a line space lever, a feed pawl on said lever, means supporting said lever on the carriage to swing about and slide longitudinally of an axis extending transversely of the axis of the

ratchet wheel, a shiftable stop mounted on the carriage out of the path of the pivotal movement of the lever and adapted to be engaged by the lever to limit the sliding movement thereof, and spring means for normally swinging the lever and feed pawl away from the ratchet wheel and sliding the lever laterally toward said stop.

22. In a typewriting machine, the combination of a platen carriage, a platen rotatably mounted on the carriage, a ratchet wheel rotatable with the platen, a line space lever, a feed pawl on said lever, means supporting said lever on the carriage to swing about and slide longitudinally of an axis extending transversely of the axis of the ratchet wheel, a shiftable stop mounted on the carriage out of the path of the pivotal movement of the lever and adapted to be engaged by the lever to limit the sliding movement thereof, spring means for normally swinging the lever and feed pawl away from the ratchet wheel and sliding the lever laterally toward said stop, and means for always arresting the swinging movement of the lever in opposite directions at the same two points.

23. In a typewriting machine, the combination of a platen carriage, a platen rotatably mounted on the carriage, a ratchet wheel rotatable with the platen, a line space lever, a feed pawl on said lever, means supporting said lever on the carriage to swing about and slide longitudinally of an axis extending transversely of the axis of the

ratchet wheel, a shiftable stop mounted on the carriage out of the path of the pivotal movement of the lever and adapted to be engaged by the lever to limit the sliding movement thereof, spring means for normally swinging the lever and feed pawl away from the ratchet wheel and sliding the lever laterally toward said stop, means for arresting the swinging movement of the lever by said spring means at a fixed point, and an overthrow-preventing pawl carried by said lever adapted to engage the ratchet wheel subsequently to the engagement of the feed pawl with said wheel.

24. In a typewriting machine, a platen feed wheel, a line-space lever, means supporting said lever to swing about and slide longitudinally of an axis extending transversely of the axis of the feed wheel, a feed pawl and an over-throw-preventing pawl carried by the lever and adapted to successively engage the feed wheel, spring means for normally swinging the lever and pawls away from the feed wheel and sliding the lever longitudinally of its pivotal axis, and a rotatably adjustable cam device mounted independently of the lever and coacting therewith to shift the lever longitudinally of its axis against the action of said spring means to vary the initial position of the lever and pawls relatively to the feed wheel.

In testimony whereof I hereunto affix my signature.

KENNETH E. MARSH.
